SURFACING RUNNER

John M. Fisher and Merle M. Eakins, Ford City, Pa., assignors to Pittsburgh Plate Glass Company, Allegheny County, Pa., a corporation of Pennsylvania

Application April 5, 1947, Serial No. 739,720

6 Claims. (Cl. 51—209)

1

This invention relates to apparatus for surfacing sheets of glass, or the like, and it has particular relation to a bonded abrasive unit and mountings therefor.

One object of the invention is to provide an improved mounting for bonded abrasive surfacing units by which a unit can be firmly held over a greater portion of its area while in position for application to work to be surfaced.

Another object of the invention is to provide an improved structure and arrangement of a chuck and bonded abrasive elements adapted to be mounted upon a surfacing machine.

Another object of the invention is to provide improved mountings for bonded abrasive elements by which rigid connections are uniformly distributed over the abrasive elements to prevent inequalities in stresses and by which portions of the connections can be removed according to the degree of wear on the work-engaging surface of the abrasive elements.

In the drawing:

Fig. 1 is a diagrammatic bottom plan of a runner unit for a surfacing apparatus; Fig. 2 is a fragmentary horizontal section, on a larger scale, taken substantially along the line II—II of Fig. 4; Fig. 3 is a fragmentary cross-section, on a larger scale, taken substantially along the line III—III of Fig. 1; and Fig. 4 is a fragmentary side elevation of a runner unit.

In one form of the invention illustrated in the drawing, an annular runner assembly 10 comprises a metal disk cap 11 that is adapted to be connected to a runner supporting mechanism of a surfacing apparatus, and an annular groove 12 is formed in the lower side of the disk cap adjacent its rim. A segmental annular abrasive structure 14 composed of bonded abrasive segments 15 has the upper edge portions thereof fitted into the groove 12 while the lower edges or rim portions 16 remain free to engage work to be surfaced. The assembly of abrasive segments 15 defines an annulus of substantially truncated conical form. Suitable cement 17 secures the upper rim portion of the annular abrasive structure 14 firmly in the groove 12. The surfacing segments 15 can be selected, as to composition, from well known types of bonded abrasive used in surfacing operations according to the nature of the work to be surfaced.

Although the position of the runner assembly as shown in the drawing is such that the axis of the annular structure 14 is substantially vertical or upright, it is to be understood that such position is illustrative for purposes of convenience in description and that the structure is adapted to operate in other positions.

2

In order that the abrasive segments 15 may be mounted and held in proper position to form an annular structure, a series of truncated conical metal rings 18, 19 and 20 of unequal diameters 5 are rigidly secured to these segments by means of horizontal bolts 21 arranged radially of each ring. The rim portions of the rings are rabbeted, as indicated at 22, for the purpose of insuring continuity of the conical surfaces of the 10 rings along the joints defining the lines of division between adjacent rings and in conformity with the contour of the inner walls of the segmental annular structure 14. The three rings thus constitute sectional ring structure. The 15 smaller or upper ring 18 is disposed at its upper edge in an annular groove 23 formed in the lower side of the disk cap 11. The annular grooves 12 and 23 are arranged so as to be coaxial with each other and with respect to the annular structure 14 and rings 18, 19 and 20.

The bolts 21 are screwthreaded into tapped openings 24 in the rings which have lugs 26 welded thereto, as indicated at 27, to insure proper depth of the tapped openings. These 25 bolts are spaced circumferentially along each ring and disposed radially thereof.

The adjacent edges of the successive segments 15 are spaced sufficiently to receive rows of the bolts 21 that are connected to the rings 18, 19 30 and 20. These bolts are disposed between adjacent spaced ends of all of the segments 15. Bushings 31 which surround the bolts are composed of softer material, such as lead, copper, or even fibrous composition, and prevent damage to the extremities of the abrasive segments which might otherwise contact the bolts during assembly of the segments or during operation of the runner assembly. The outer ends of the bolts are provided with clamping heads 32 having converging outer walls 33 which are complementary to similar converging or beveled end walls or faces 34 of the segments 15. The clamping heads 32 are recessed, as indicated at 35, to receive the heads of the bolts in countersunk relation. The shanks of these bolts extend through openings 36 in the central portions of the clamping heads. This arrangement of elements is designed for the purpose of preventing any projections beyond the outer circumferential surfaces of the 40 abrasive segments. Suitable gaskets 37 composed of yieldable material, such as fiber composition, rubber composition, or the like, are disposed between opposed complementary faces 33—34. By tightening the bolts 21 in the metal 45 rings the surfaces 33 of the clamping heads 32 are wedged between the respective adjacent ends of the segments 15 and against the cushioning 50

gaskets 37. The several inner faces of the segments 15 at locations on opposite sides of the respective bolts 21 are also cushioned by means of gaskets 38 disposed between the segments 15 and the surfaces of the rings.

It is to be noted that the bolts 21 are disposed radially at points spaced circumferentially of each ring. After the abrasive segments have been worn a predetermined degree in their operation, the lower ring 20 can be removed by releasing the bolts connected thereto. Upon releasing these bolts the ring is free to fall from the conical or flaring inner walls of the annular structure 14. In like manner, the next ring 19 is adapted to be removed after the segmental abrasive structure has been worn along its lower rim to such extent that it is nearing the edge of such next ring 19. In this manner the segments 15 can be firmly mounted with respect to the rings and supporting disk 11, and the several rings can be successively removed according to the degree of wear on the surfacing rim, while still maintaining proper rigid mounting and distribution of stresses in the annular abrasive structure.

It is important that the segments be cemented firmly to the disk cap 11. The bond between the abrasive segments 15 and the metal disk in the groove 12 can be effected by cementing with such materials as pitch, Rose's metal (an alloy of bismuth, lead and tin), type metal or other eutectic alloys or magnesium oxychloride.

Although only one form of the invention has been shown and described in detail, it will be apparent to those skilled in the art that the invention is not so limited, but that various changes can be made therein without departing from the spirit or scope of the invention as exemplified in the appended claims.

We claim:

1. In a runner assembly for surfacing apparatus, a runner cap of plate form, a ring connected edgewise upon the bottom of the cap, additional rings disposed in coaxial relation to the first ring, adjacent rings having rim portions overlapping in axial directions and having their wall surfaces substantially flush with one another, bonded abrasive material defining an annular contour and arranged in coaxial relation to the rings, each ring having a series of connections spaced at intervals circumferentially of the ring and securing the ring and abrasive material in rigid relation.

2. A surfacing assembly comprising a supporting member, said member having coaxial grooves in one side thereof, ring structure having a rim disposed in one of said grooves and leaving an opposite rim free, bonded abrasive material defining an annular contour and mounted in the other groove, said abrasive material including a surfacing rim extending axially beyond the free rim of the ring structure, and radial connections securing the annular abrasive material and ring structure in rigid relation.

3. In a runner assembly for surfacing apparatus, a supporting cap having an annular groove on one side thereof, bonded abrasive material of annular form having an upper rim thereof mounted in said groove, rings disposed coaxially in edge to edge engagement and coaxially of the annular abrasive material, and means for demountably securing the rings separately to the annular material, said rings having interfitting edge to edge engagement holding adjacent ring edges against relative lateral displacement, and being successively removable therefrom.

4. In a runner assembly for surfacing apparatus, a sectional ring structure of truncated conical form and including ring sections whose lines of division are in planes disposed transversely of the axis of the ring structure, segments of abrasive material mounted circumferentially about the ring structure and assembled in the form of a truncated cone, and means for demountably connecting each ring section to the abrasive sections, adjacent marginal portions of said sections having interlocking means holding them against relative lateral displacement and said sections being free to fall axially from one another upon release of said means.

5. In a rotatable runner assembly for surfacing apparatus and having an upright axis, a supporting cap having inner and outer coaxial grooves on the lower side thereof, a bonded abrasive segmental annulus composed of segments defining a surfacing rim disposed in a plane transversely of the axis of the annulus and anchored in the outer groove, said segments being disposed successively about the circumferential extent of the annulus, adjacent segments having converging wall portions, metal ring structure interfitting in coaxial relation with the segmental annulus in axially spaced relation to the surfacing rim and having its upper rim anchored in the inner groove, said ring structure including ring sections with adjacent marginal portions of the sections in assembled relation being interlocked against lateral displacement, each ring section having radial openings therein registering with the lines of division between the several segments, and fastening means separately mounted in the openings of each ring section and having portions disposed in wedged relation on said converging wall portions to secure in rigid relation the annulus and ring structure.

6. In a runner assembly for surfacing apparatus, a segmental annulus composed of bonded abrasive segments defining a surfacing rim disposed in a plane transversely of the axis of the annulus, adjacent segments of the annulus having oppositely beveled and juxtaposed extremities, metal ring sections interfitting in coaxial relation with the annulus, adjacent marginal portions of the rim sections in assembled relation being rabbeted and interlocked against lateral displacement, each ring section having openings therein registering with lines of division between the segments, fastening members mounted in said openings, bushings on said fastening members between adjacent extremities of said segments for cushioning said segments, said fastening members having flaring portions bearing against adjacent beveled portions of said segments.
